UNITED STATES PATENT OFFICE.

EDWARD CHARPIER, OF CHICAGO, ILLINOIS.

ELECTRIC SWITCH, FUSE, AND PROTECTOR THEREFOR.

1,156,887.

Specification of Letters Patent.

Patented Oct. 19, 1915.

Application filed February 13, 1914. Serial No. 818,444.

To all whom it may concern:

Be it known that I, EDWARD CHARPIER, a citizen of the United States, residing at the city of Chicago, in the county of Cook and State of Illinois, have invented certain new and useful Improvements in Electric Switches, Fuses, and Protectors Therefor, of which the following is a specification.

The invention relates to an improvement 10 in electric switches, fuses, and protectors therefor, being particularly directed to a device of this character adapted to be arranged intermediate the service mains and branch lines the construction providing for the convenient and expeditious renewal of burned 15 out fuses, and also for locking the switch element proper against unauthorized manipulation.

The main object of the present invention 20 is the provision of an electric switch, fuse and protector including a casing having terminal contacts for the service mains and relatively spaced contacts for the branch line connections, fuse carriers being rotatably 25 mounted adjacent said contacts to permit the introduction of successive fuses into the circuit, as required, the switch element proper being adapted to be locked in open relation to prevent unauthorized closing of the 30 circuit.

The invention in the preferred form of details will be described in the following specification, reference being had particularly to the accompanying drawings, in 35 which:—

Figure 1 is a plan view of the switch, fuse, and protector, constructed in accordance with the present invention. Fig. 2 is a similar view with the cover of the casing 40 removed. Fig. 3 is an enlarged broken sectional view illustrating one of the main set of contacts, and the adjacent fuse carrier. Fig. 4 is a diagrammatic view illustrating the wiring of the device.

In the accompanying drawings, the improved device is shown to include a casing 1 having side and end walls and a cover 2 adapted to snugly fit the same, the upper edges of the side and end walls of the casing 50 being provided with staples 3 to pass through openings 4 in the cover, the projecting portions of the staples receiving sealing strips 5, whereby to lock the cover against unauthorized removal.

Projecting from one of the side walls of the casing is an insulating block 6, formed

to provide for the connections of the service mains and branch wires thereto. The block is shown in the present instance as providing for the usual three such mains, the space 60 contacts being the same in each instance. The contacts include vertically alined binding posts 7 arranged on the respective upper and lower surfaces of the block, one of the service mains 8 being connected to the 65 upper post and one of the branch conductors, 9, connected to the lower post. Secured to the respective binding posts are spaced contact plates 10 and 11, which plates extend beyond the proximate edge of the block. 70

As previously stated, there are three such sets of contacts, and three fuse carriers are illustrated as coöperating therewith, one fuse carrier for each set of contacts. Each fuse carrier, it being understood that all are 75 identical, includes a shaft 12 rotatably mounted in an insulating block 13 supported on the bottom of the casing, said shaft being provided at an appropriate point in its length with a drum or cylindrical casing 14. 80 The upper and lower edges of the drum, which is preferably of porcelain or similar insulating material, are provided with contact posts 15 and 16, which include laterally projected spring contact strips 17 and 18. The respective vertically alined contact posts 15 and 16 are connected by fuse strips 85 19 of any suitable or preferred type.

The drum is so mounted on the shaft that the respective contact plates 17 and 18 will, 90 in the rotation of the drum, be forced between the space contact plates 10 and 11 of the upper and lower set of adjacent main contacts, so that by moving the drum to arrange such contacts, the particular fuse is 95 placed in circuit.

Within the casing is arranged an ordinary three pole switch 20 to the fixed contacts 21 of which are connected conductors 22 leading to the house or other service through 100 the usual meters 23. The movable contacts 24 of the switch are in circuit with the branch conductors 9 leading from the main contacts. It is designed, as part of the present invention, to lock this switch in open relation when desired, and for this purpose I mount in the bottom of the casing a shaft 25 having a slotted arm 26 to engage a pin 27 projecting from the cross bar joining all of the plates or movable contacts of the 105 switch.

Both the shaft 25, and the shafts 12 ex-

tend through openings in the top of the casing, being beyond said top of angular form in cross section, as shown, whereby to receive an operating wrench, as 28. The upper end of each shaft 12 is provided with a cam plate 29, the edge depressions 30 of which are adapted to coöperate with appropriately formed terminals 31 of spring strips 32, projecting from an abutment or block 33 secured on the casing cover, whereby the drums are held in proper circuit closing relation by the spring elements.

The upper end of the shaft 25 is also of angular formation in cross section and a hasp member 34 is formed with a socket end to fit the angular end of the shaft, said hasp member being formed with an opening adapted to register with a similar opening in a projection 35, rising from the cover, the registering openings receiving a padlock 36, to lock the shaft 25 against movement.

The edge of the casing is formed with a conduit projection 37 through which the mains 8 enter the casing, a similar conduit projection 38 being provided for the passage of the conductors 22 intermediate the switch and meters. I also prefer to arrange a housing 39 on the side wall of the casing about the conduit 38 and form said housing with a curved recess 40 to receive the meter.

From the above description, it will be apparent that when desired a new fuse strip may be introduced into any connection between the service and branch conductors, this operation being simply and readily accomplished by the rotation of the particular fuse carrier through actuation of the wrench. From the drawings, it will be apparent that

the lock 36 holds the switch 20 in open condition, but that when it is desired to close the switch to establish the connection, the pad-lock may be removed, the hasp 34 lifted from the shaft 25, and the wrench 28 applied thereto to close the switch. 40 45

The device provides a combined switch, fuse carrier and protector in a single casing, which may remain closed until necessary to remove the fuses, while at the same time permitting the introduction of new fuse strips 50 into the service, and the locking of the parts against unauthorized operation.

What is claimed is:

A combined switch fuse and protector comprising a casing, conductors therein, an insulating block supported in the casing, spring strips forming the terminals of the respective conductors and secured in spaced relation to said block, each of said strips including two normally spaced sections, a member rotatably mounted within the casing adjacent the block, independent strips carried by said member to fit between the sections of the respective strips, fuses connecting said last mentioned strips, a block carried by and movable with said member, said block being arranged beyond the casing and formed with a notch for each fuse line of the member, each fuse having a notch in alignment therewith, and means secured upon the casing to coöperate with the notches to temporarily restrain the movement of the member in connected relation. 55 60 65 70

EDWARD CHARPIER.
